UNITED STATES PATENT OFFICE.

ARTHUR D. WHIDDEN, OF ELYRIA, OHIO.

ENGINE-VALVE.

1,127,837.

Specification of Letters Patent. Patented Feb. 9, 1915.

Application filed June 10, 1913. Serial No. 772,849.

To all whom it may concern:

Be it known that I, ARTHUR D. WHIDDEN, citizen of the United States, residing at Elyria, in the county of Lorain and State 5 of Ohio, have invented certain new and useful Improvements in Engine-Valves, of which the following is a specification.

My invention relates to new and useful improvements in engine valves and more 10 particularly to rotary valves for use in connection with multiple cylinder, internal combustion engines, the primary object of my invention being to provide a rotary valve which will control both the supply of explosive 15 mixture and the exhaust in an engine of the four-cycle type having a plurality of cylinders.

A further object of my invention is to accomplish the above by means of a tubular 20 cylindrical valve casing, preferably cast integrally with the cylinders and a hollow cylindrical valve fitting within the valve casing and provided with ports arranged to register at proper intervals with a plurality 25 of ports formed in the valve casing, the inner cylinder forming the valve proper being closed at its ends and divided by transverse partitions into a plurality of 30 separate chambers.

35 A further object of my invention is to so arrange and position the various ports that the pressure through the exhaust ports and inlet ports equalize each other, thereby eliminating the greater part of the friction between the valve and valve casing.

40 A further object of my invention is the provision of a peculiar type of packing ring for use about the ports of the valve casing and engaging against the valve proper to prevent all leakage of either the explosive mixture or exhaust gases between the valve and its casing. And a still further object 45 of my invention is to so cast the valve casing with the engine cylinders that the cylinders and casing will be surrounded and cooled by a single water jacket.

With these and other objects in view, my invention will be more fully described, illustrated in the accompanying drawings, and 50 then specifically pointed out in the claims which are attached to and form a part of this application.

In the drawings: Figure 1 is a central, vertical, longitudinal sectional view taken through a four-cylinder engine equipped 55 with my improved rotary valve; Fig. 2 is a horizontal, longitudinal sectional view taken on the line 2—2 of Fig. 1, showing the valve construction; Fig. 3 is a vertical transverse sectional view taken on the line 3—3 of Fig. 60 2 looking in the direction of the arrows; Fig. 4 is a perspective view of the valve removed from the valve casing; Fig. 5 is a detail sectional view taken on the line 5—5 of Fig. 2, showing the construction of one 65 of the packing rings; Fig. 6 is an unassembled perspective view of one of the packing rings removed from the valve casing.

Corresponding and like parts are referred to in the following description and indicated in all the views of the drawings by the same reference characters.

For the sake of clearness and to insure a full understanding of the construction and operation of my improved valve I have 75 illustrated the same in connection with a four-cylinder, four-cycle internal combustion engine of conventional type, it being understood that it may be employed with 80 equally good results with an engine having 85 any number of cylinders. The engine consists primarily of two castings 10 and 11, the former forming the crank casing of the engine and the latter including the cylinders and valve casing, together with the 90 various passages leading from the cylinders to the casing. These castings are bolted or otherwise secured together in the usual manner and the front and rear walls of the casting 10 or crank case are provided with 95 aligned bearings 12 to receive a crank shaft 13. Brackets 14 extend upwardly from the bottom of the crank casing and are provided with bearings 15 to support intermediate portions of the crank shaft.

95 The cylinders and valve casing are preferably cast as a unit in order to prevent all leakage either of the explosive mixture, exhaust gases or water from the water jacketing of the cylinders and valve and said 100 casting includes an outer casing 16 and cylinders 17, 18, 19 and 20, a hollow cylindrical valve casing 21 extending in spaced relation above the tops of the cylinders and longitu-

dinally of the outer casing 16 and a plurality of ducts 22 forming passages for the admission of the explosive mixture to the cylinders and the escape of the exhaust gases therefrom. The space within the outer shell 16 surrounding the cylinders, valve casing and ducts forms a water chamber through which the circulation of water may be maintained in any desired manner, 10 not shown, to prevent overheating of the cylinders and valve.

Pistons 23 are mounted in the cylinders and operatively connected by piston rods 24 with the wrist pins 25 of the crank shaft.

15 The valve casing 21 opens at its ends through the front and rear walls of the outer casing 16 and one end of said valve casing is closed by a threaded cap 26, while the other end is closed by a threaded cap 27 provided centrally with an opening 28 for the passage of a trunnion formed upon one end of the valve proper and by which the valve is rotated in its casing, as will be later explained.

25 The valve casing is provided along the horizontal plane of its axis and upon both sides with a multiplicity of ports 29, 30, 31, 32, 33, 34, 35, 36, 37, 38, 39, 40 and 41, the ports upon one side being arranged in 30 staggered relation with respect to the ports upon the other. Ducts 42 lead from these ports to aligned ports in the casing 16, while the ports 30 and 31 communicate with the cylinder 17, ports 33 and 34 with the cylinder 18, ports 36 and 37 with the cylinder 19 and ports 39 and 40 with the cylinder 20, all through the ducts 22, previously described. The carburetor manifold 43 has branches 44 and 45 leading to the ports of 40 the outer casing 16 communicating with the valve casing ports 32 and 38, and an exhaust manifold 46 has branches 47, 48 and 49 leading to the ports of the outer casing 16 communicating with the valve casing 45 ports 29, 35 and 41, respectively. The ports 31, 33, 37 and 39 constitute the fuel supply ports of the cylinders 17, 18, 19 and 20, respectively, while the ports 30, 34, 36 and 40 constitute the exhaust ports of said cylinders.

50 A valve proper 50 is mounted for rotation in the valve casing and this valve consists of a hollow cylindrical shell or body fitting closely within the valve casing and 55 bearing by one end against the cap 26 and by its other end against the cap 27, both ends being closed and said latter end being provided with a centrally formed trunnion 51 which projects through the opening 28 60 of the cap. This trunnion carries a sprocket 52 and a sprocket chain 53 is trained about the sprocket 52 and about a second sprocket 54 carried upon the forward end of the crank shaft 13, the relative size of the 65 sprockets 52 and 54 being such that the

valve is turned once during every two revolutions of the crank shaft. Although I have shown the valve as driven by a chain and sprockets from the crank shaft, it will of course be understood that the valve may 70 be driven in any suitable manner, the idea being merely to provide means for rotating the valve at half the speed of rotation of the crank shaft. This valve body proper is divided into a plurality of chambers 55, 56, 75 57, 58 and 59 by means of its closed ends and a plurality of spaced apart transversely extending partition walls 60, 61, 62 and 63. These chambers constitute the fuel supply and exhaust chambers of the valve, the 80 chambers 56 and 58 supplying fuel from the carburetor manifold to the cylinders and the chambers 55, 57 and 59 conveying the exhaust gases from the cylinders to the exhaust manifold as will be later explained. 85 For this reason, the peripheral wall of the chamber 55 is provided with ports 64 and 65 formed to simultaneously register with the ports 29 and 30, respectively of the casing in one position of the valve to permit 90 the escape of the exhaust gases from the cylinder 17 through the ports 30 and 65 to the chamber 55 and from this chamber through the ports 64 and 29 to the exhaust manifold. These ports are longitudinally 95 spaced apart and are formed in opposite sides of the valve body.

The wall of the chamber 56 is provided with ports 66 and 67 oppositely disposed and longitudinally spaced apart and with 100 ports 68 and 69 also oppositely disposed with respect to each other and longitudinally spaced apart, the ports 67 and 69 being midway longitudinally between the ports 66 and 68 and disposed at substantially ninety degrees from each other.

The wall of the chamber 57 is provided with ports 70—71 and 72—73, the ports 71 and 73 being directly opposite each other both circumferentially and longitudinally, 110 while the ports 70 and 72 are disposed longitudinally one upon either side of the ports 71 and 73, the former, that is the port 70, being beside the port 73, while the latter, that is the port 72, is beside the port 71. 111 In like manner, the wall of the chamber 58 is provided with ports 74 and 75 oppositely disposed and longitudinally spaced apart and with ports 76 and 77 also oppositely disposed with respect to each other and 112 longitudinally spaced apart, the ports 75 and 77 being midway longitudinally between the ports 74 and 76 and disposed at substantially ninety degrees from each other.

The wall of the chamber 59 is provided with ports 78 and 79 oppositely disposed, longitudinally spaced apart and arranged to simultaneously register with the ports 40 and 41, respectively of the valve casing. 130

5 The various ports of each chamber are not only arranged with respect to each other as above described, but the ports of each chamber are disposed in a certain way with respect to the ports of all other chambers in order to insure a uniform and proper firing of the cylinders. Explosions occur in the cylinders, when the engine is running, in the usual order common to most four-cylinder, four-cycle engines, that is, assuming that the first explosion is in the cylinder 17, in the cylinders 19, 20, 18, 17, 19, etc.

10 The fuel supply for the engine passes through the manifold 43 to the manifold branches 44 and 45 and so, in proper positions of the valve, to the valve chambers 56 and 58. In one position of the valve, fuel passing through the branch 44 passes through the valve casing port 32 and valve port 67 into the chamber 56 and from this chamber through the valve port 66 and valve casing port 31 to the cylinder 17. In yet another position of the valve, fuel passes from the branch 44 through the valve casing port 32 and valve port 69 into the valve chamber 56 and from this chamber through the valve port 68 and valve casing port 33 to the cylinder 18. In another position of the valve, fuel passes through the manifold branch 45 through the valve casing port 38 and valve port 75 to the valve chamber 58 and from this valve chamber through the valve port 74 and valve casing port 37 to the cylinder 19. Again, in still another position of the valve, fuel passes from the branch 45 through the valve casing port 38 and valve port 77 into the valve chamber 58 and from this valve chamber through the valve port 76 and valve casing port 39 to the cylinder 20. It will therefore be seen that the fuel supply passes from the manifold through the valve chambers 56 and 58 to the various cylinders of the engine. In like manner, the exhaust of the various engine cylinders passes into one or the other of the valve chambers 55, 57 and 59 and to the exhaust manifold 46 through the exhaust manifold branches 47, 48 and 49, respectively. More specifically, in one position of the valve, the exhaust gases from the cylinder 17 pass through the valve casing port 30 and valve port 65 into the valve chamber 55 and from this valve chamber through the valve port 64 and valve casing port 29 to the branch 47 of the exhaust manifold. In another position of the valve, the exhaust gases from the cylinder 18 pass through the valve casing port 34 and valve port 70 into the valve chamber 57 and from this chamber through the valve port 71 and valve casing port 35 to the branch 48 of the exhaust manifold. In yet another position of the valve, the exhaust gases from the cylinder 19 pass through the valve casing port 36 and valve port 72 into the

valve chamber 57 and through the valve port 73 and valve casing port 35 into the branch 48 of the exhaust manifold. In like manner, in still another position of the valve, the exhaust gases from the cylinder 20 pass through the valve casing port 40 and valve port 78 into the valve chamber 59 and from this valve chamber through the valve port 79 and valve casing port 41 into the branch 49 of the exhaust manifold.

15 From the above description, the operation of the valve will be readily understood. As shown, in Figs. 1 and 2 of the drawings, the cylinder 17 is on the beginning of its impulse stroke, the cylinder 18 on the beginning of its exhaust stroke and the cylinders 19 and 20 at the beginning of their compression and intake strokes, respectively. In this position of the valve, the exhaust 20 valve ports 64 and 65 are so located that a quarter revolution of the valve will bring them into alinement with their respective valve casing ports 29 and 30 to permit the exploded gases from the cylinder 17 to 25 escape, as at that time, due to the half speed drive of the valve, the cylinder 17 will be at the beginning of its exhaust stroke.

25 The valve ports 66 and 67, in Fig. 2, are directly opposite their respective valve casing ports 31 and 32 in order that, after a half rotation of the valve, at which time the cylinder 17 will be at the beginning of its intake stroke, they may register with 30 such valve casing ports to permit passage 35 of fuel from the manifold 43 to the cylinder 17. The valve ports 68 and 69, on the other hand, are but a quarter revolution from their respective valve casing ports 33 and 32 in order that they may, after a quarter revolution of the valve, that is a half revolution of the crank shaft, be in alinement with 35 their respective valve casing ports to permit supply of fuel to the cylinder 18 which will then be at the beginning of its intake stroke.

40 As previously mentioned, the cylinder 18 is at the beginning of its exhaust stroke, as shown in Fig. 2, and for that reason the valve ports 70 and 71 are in alinement with 45 their respective valve casing ports 34 and 35 to permit the escape of the exhaust gases from the cylinder 18 to the exhaust manifold 46. As the exhaust from the cylinder 19 will not occur until after one complete revolution of the crank shaft or half revolution of the valve, the valve ports 72 and 73, which constitute the exhaust valve ports for this cylinder, are located diametrically opposite their respective valve casing ports 50 36 and 35. The cylinder 19 being at the beginning of its compression stroke, the valve ports 74 and 75 are located one-half revolution from their respective valve casing ports 37 and 38 in order that after one 55 complete rotation of the crank shaft, which

will bring the cylinder 19 to the beginning of its intake stroke, they may be in alignment with their respective valve casing ports to supply fuel from the manifold 44 to the cylinder 19.

5 Inasmuch as the cylinder 20 is at the beginning of its intake stroke, the valve ports 76 and 77 are in alignment with their respective valve casing ports 39 and 38 to 10 permit passage of fuel from the manifold 44 to the cylinder 20. As after one-half revolution of the crank shaft, the cylinder 20 will be at the beginning of its exhaust stroke, the valve ports 78 and 79 are located

15 one-quarter rotation of the valve from their respective valve casing ports 40 and 41 to permit escape of exhaust gases from the cylinder 20 to the manifold 46 at the proper time.

20 The above description discloses the construction and arrangement of my improved valve and also explains with sufficient clearness the manner in which it operates to control the supply of charges of combustible

25 gas to the various cylinders and the escape of the exhaust gases therefrom. It will, however, be apparent that it is of the utmost importance that all leakage of either the explosive gas or the exhaust gases between the 30 valve and valve casing be prevented as the valve would be practically worthless if such leakage was permitted. For this reason I surround each of the valve casing ports with a packing ring which engages against the 35 outer peripheral face of the valve at all times and which absolutely prevents all leakage.

Referring more specifically to Figs. 5 and 6, which best show the construction and arrangement of the packing rings, it will be noted that the inner face of the valve casing 21 adjacent each of the ducts 42 is provided with an annular seat 80 to receive a packing ring 81 of any suitable metal, the inner face 45 of which is shaped to conform with and bear against the peripheral face of the valve as clearly shown in both Figs. 5 and 6. Although the seat and packing ring are described as shown as annular, it will of course be understood that they may be formed in any desired shape. The outer face of the packing ring is provided with an outwardly directed annular flange 82 which extends in parallel spaced relation to the 55 wall of the duct 42 and a packing ring 83 of asbestos, mineral wool or other suitable material is seated between the wall of the duct and this flange. A clamping ring 84 is then inserted to bear against the packing ring 83 to force the same into close engagement 60 with the packing ring 81, its flange 82 and the wall of the duct 42. This clamping ring 84 is provided with two or more spaced apart legs 85 which extend longitudinally 65 of the duct 42 and against which the inner

edge of a clamp screw 86, threaded into the outer end of the duct 42, bears. The clamp screws threaded into the ducts leading to the ports 30, 31, 33, 34, 36, 37, 39 and 40 are closed at their outer ends, while the clamp screws threaded into the ducts leading to the ports 29, 32, 35, 38 and 41 are provided with openings to receive the free ends of the branches of the manifolds 43 and 46. The above described packing rings prevent all leakage of gas from the valve and insure proper compression in the cylinders providing the pistons of the cylinders fit tightly.

70 The top of the outer casing 16 and the upper portion of the valve casing 21 are provided with aligned bores to receive lubricating pipes 87 by means of which oil may be supplied to the valve between it and its casing. Threaded passages 88 leading 75 through the casing 16 and upper portions of the cylinder walls are adapted to receive spark plugs by which the charges in the cylinders may be ignited.

75 Having thus described the invention, what is claimed as new is:

1. In a gas engine valve, a cylindrical valve casing having inlet ports, one adapted for communication with an inlet manifold and one for communication with an engine cylinder, and exhaust ports one adapted for communication with an exhaust manifold and one for communication with the cylinder; a hollow cylindrical valve closed at its ends rotatable in the valve casing having oppositely disposed inlet ports and oppositely disposed exhaust ports arranged for registration with the inlet and exhaust ports of the valve casing, and a partition extending between the inlet and exhaust ports of the valve dividing the same into inlet and exhaust chambers.

90 2. In a gas engine valve, a cylindrical valve casing having oppositely disposed inlet ports, one adapted for communication with an inlet manifold and one for communication with an engine cylinder, and oppositely disposed exhaust ports one adapted for communication with an exhaust manifold and one for communication with the cylinder; a hollow cylindrical valve closed at its ends rotatable in the valve casing having inlet and exhaust ports arranged for registration with the inlet and exhaust ports of the valve casing, and a partition extending between the inlet and exhaust ports of the valve dividing the same into inlet and exhaust chambers.

95 3. In a gas engine valve, a cylindrical valve casing having inlet ports, one adapted for communication with an inlet manifold and one for communication with an engine cylinder, and exhaust ports, one adapted for communication with an exhaust manifold and one for communication with the cyl- 100

inder; a hollow cylindrical valve closed at its ends rotatable in the valve casing having inlet and exhaust ports arranged for registration with the inlet and exhaust ports of the valve casing, and a partition extending transversely between the inlet and exhaust ports of the valve dividing the same into inlet and exhaust chambers.

4. In a gas engine valve, a cylindrical valve casing having oppositely disposed inlet ports, one adapted for communication with an inlet manifold and one for communication with an engine cylinder, and oppositely disposed exhaust ports one adapted for communication with an exhaust manifold and one for communication with the cylinder, and a hollow valve rotatable in the valve casing and ported and partitioned to provide chambers to establish communication between the inlet ports of the valve casing and between the outlet ports thereof.

5. In a gas engine valve, a cylindrical valve casing having oppositely disposed inlet ports, one adapted for communication with an inlet manifold and one for communication with an engine cylinder, and oppositely disposed exhaust ports one adapted for communication with an exhaust manifold and one for communication with the cylinder, a valve rotatable in the valve casing and ported to establish communication between the inlet ports of the valve casing and between the outlet ports thereof, and packing rings disposed in seats in the valve casing surrounding the ports thereof and bearing against the valve.

6. In a gas engine valve, a cylindrical valve casing having a plurality of pairs of inlet ports, the said pairs being spaced apart longitudinally and the ports of each pair being oppositely disposed, one port of each pair being adapted for communication with an inlet manifold and the other port of each pair for communication with an engine cylinder, said casing being further provided with a plurality of pairs of exhaust ports, the pairs of exhaust ports being longitudinally spaced apart, while the ports of each pair are disposed oppositely, one exhaust port of each pair being adapted for communication with an exhaust manifold and the other exhaust port of each pair for communication with a cylinder, a hollow cylindrical valve closed at its ends rotatable in the valve casing and having a plurality of pairs of inlet ports and a plurality of pairs of exhaust ports, the ports of each pair being oppositely disposed, the ports of each pair of inlet ports being arranged for simultaneous registration with the ports of the corresponding pair of valve casing inlet ports and the ports of each pair of valve exhaust ports being arranged for simultaneous communica-

cation with the corresponding ports of a pair of valve casing exhaust ports, and a plurality of transversely extending partitions dividing the valve into a plurality of chambers, all of the inlet ports of the valve communicating with certain of the chambers while all of the outlet ports of the valve communicate with certain of the remaining chambers.

7. In a gas engine valve, a cylindrical valve casing having a plurality of inlet ports certain of which are diametrically disposed with respect to others, said ports being arranged in groups longitudinally of the valve casing, said valve casing further having a plurality of exhaust ports certain of which are diametrically disposed with respect to others, said exhaust ports being arranged in groups longitudinally of the casing, a hollow cylindrical valve closed at its ends rotatably mounted in the valve casing and provided with a plurality of pairs of ports, the ports of each pair being oppositely disposed with respect to each other, there being a valve port for each valve casing port and the valve ports being so arranged with respect to the valve casing ports that in some position of the valve the ports of each pair of valve ports will register with certain of the ports of its corresponding group of valve casing ports, and a plurality of transversely extending partition walls dividing the valve into a plurality of chambers, each wall being disposed between the valve ports corresponding to a group of valve casing inlet ports and a group of valve ports corresponding to a group of valve casing exhaust ports.

8. In gas engines, an engine casing, a plurality of cylinders, a hollow cylindrical valve casing having inlet ports along one side, each communicating through ducts with one of the cylinders, a plurality of exhaust ports along the other side, each communicating through ducts with one of the cylinders, a plurality of carbureter manifold ports along said latter side and a plurality of exhaust manifold ports along the former side, and a cylindrical valve rotatable in the valve casing so ported that in a complete revolution it establishes communication between each inlet port and some one of the carbureter manifold ports and between each exhaust port and some one of the exhaust manifold ports.

9. In gas engines, an engine casing, a plurality of cylinders, a hollow cylindrical valve casing having inlet ports and exhaust ports communicating through ducts with the cylinders and inlet and exhaust ports adapted for communication through other ducts with carbureter and exhaust manifolds, said ports being formed in opposite sides of the casing and all in a common plane through its axis, and a cylindrical

valve rotatable in the casing and so ported that in a complete revolution it establishes communication between each inlet port and some one of the carburetor manifold ports 5 and between each exhaust port and some one of the exhaust manifold ports.

In testimony whereof I affix my signature in presence of two witnesses.
